WITNESS:

ATTORNEY

UNITED STATES PATENT OFFICE.

JOHN A. MELHOUSE, OF KIEF, NORTH DAKOTA.

HARNESS ATTACHMENT.

Application filed April 18, 1923. Serial No. 632,974.

To all whom it may concern:

Be it known that I, JOHN A. MELHOUSE, a citizen of the United States, residing at Kief, in the county of McHenry and State 5 of North Dakota, have invented new and useful Improvements in Harness Attachments, of which the following is a specification.

The object of this invention is to provide 10 tension means for preventing the reins of a double harness from getting under the tongue of a vehicle.

A further object is to effect this result by 15 the use of a tension device applied to each cross line or rein, near the point where it is connected with the bit.

A further object is to provide a tension device which shall consist of a coiled spring 20 and means thereon for engaging one of the reins, and a tubular casing which receives the spring when contracted, the casing having means on one end thereof for connection with another element of the harness.

With the foregoing and other objects and 25 advantages in view, the invention consists in the novel construction and arrangement of elements, described and claimed, it being understood that modifications may be made within the scope of the claim without departing from the spirit of the invention.

In the drawings, Figure 1 is a perspective view of the device applied to the reins of a double harness; Figure 2 is an elevation of the device, with portions of the casing appearing in longitudinal section; Figure 3 is 35 a view transversely through the casing 20 of Figure 2; Figure 4 is a detail view of a device for connecting a rein with the tension device.

The cross reins are designated 10 and 11, and these reins or lines pass through the usual rings 12 and 13, and have their ends connected with the rings 14 and 15 of the 40 bits of the respective set of harness.

The tension devices, which may also be referred to as spreaders, in the sense that they keep the reins spread or taut, include coiled springs 17, each having connected therewith a loop 18 for receiving the rein.

It will be observed from the drawing that 50 this device 18 comprises a piece of wire or the like including reversely formed loop portions each having an open end as shown, and one of said loops having barbs for engagement with a rein, and the other including a U member 18' for engagement by ring 17' of spring 17.

A tubular casing 20 is provided with a closed end 21 in which one end of the spring is secured, the opposite end of the casing 60 being open. The closed end has a ring or equivalent device 22 formed thereon, and this device is secured to an adjacent element of the harness, as for instance, the element 23, or the hame. The spring maintains the required tension, and prevents the rein from getting under the tongue, and the casing acts as a guard member, and prevents interference with the operation of the springs, 65 as far as possible, and annoyance which 70 would be caused by the latter engaging portions of the harness, or contacting with the neck of the horse.

What is claimed is:—

In a device of the character described, a 75 coiled spring, a tubular casing therefor having an open end and a closed end, means to secure one end of the spring to the closed end of the casing, a member having reversely formed loop portions, open at their ends, a 80 spring engaging device on one loop portion, rein engaging devices on the other loop portion, and means for attaching said casing to a harness part.

In testimony whereof I affix my signature.

JOHN A. MELHOUSE.
